Patented Dec. 28, 1965

203,349

GAS IGNITER GUN

Harold I. Gross, Beverly Hills, Calif., assignor to National Silver Company, New York, N.Y., a corporation of New York

Filed Feb. 5, 1965, Ser. No. 83,703

Term of patent 14 years

(Cl. D48—27)

FIGURE 1 is a side elevational view of a gas igniter gun, or similar article, showing my new design;

FIGURE 2 is a top plan view thereof;

FIGURE 3 is a rear end elevational view thereof; and

FIGURE 4 is a front end elevational view thereof.

I claim:

The ornamental design for gas igniter gun, or similar article, as shown.
